UNITED STATES PATENT OFFICE.

ORLO G. CRANNELL, OF REVERE, MASSACHUSETTS, ASSIGNOR OF TWO-FIFTHS TO ORLO M. CRANNELL, OF REVERE, MASSACHUSETTS.

VENTILATING SYSTEM.

Application filed July 6, 1923. Serial No. 649,876.

This invention relates to ventilating systems and more particularly to ventilating systems for refrigerating rooms wherein perishable products such as meat and the like are stored.

The principal object of the invention is the provision of a ventilating system wherein atmospheric or fresh air is introduced into a room at a lower temperature than the temperature of the air in the room and whereby the stale air will be simultaneously exhausted from the room.

Another object of the invention is to provide a system of the class mentioned wherein the exhaust air from the room is utilized for pre-cooling the fresh air before its entrance into the cooling device.

Another object of the invention is the provision of a ventilating system in which is arranged a cooling device wherein the fresh air is cooled to a temperature below the temperature of a room, the fresh air entering the top of the device and passing downward around a coil containing a refrigerant, and thence into the room at the bottom of the device.

A still further object is to provide a ventilating system which is simple in construction, cheap and easy of operation and highly efficient for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:

The figure is a vertical sectional view taken through a room and showing my system installed therein.

In chilled rooms for the storing of meats and like perishable foods, it has been the objection that when a chilled room is shut tight over night or during holidays the products do not keep as well as they do during working hours when the doors are continuously being opened in carrying on a day's work, that is, during working hours the doors are opened enough to permit fresh air from the outside to enter the room, thereby freshening up the air and keeping the products, regardless of the fact that the temperature of the room has been higher during such times.

This is conclusive proof that the temperature

alone does not govern the keeping qualities of products, but the condition of air as to freshness is as great a factor as the temperature itself, and with the knowledge of this in mind I have conceived the idea of bringing fresh air from the outside of a building into an insulated, artificially cooled chamber, which chamber is tightly closed except for an air duct running from the top of the chamber to the outside atmosphere, and a cold air duct running to the bottom of the room to be ventilated.

Referring more particularly to the drawing, the reference numeral 10 designates a refrigerating room, which room of course may be chilled by the usual ammonia pipes not shown in the drawing. It is in connection with this type of room that my invention is primarily intended for use, but it is to be understood that the same principle may be adopted for ventilating any other type of room desired.

Arranged within the room 10 at one end thereof is a cooling device 11 which comprises spaced inner and outer cylindrical walls 12 and 13 respectively, the space between the walls receiving an insulating substance such as cork 14. The top of the cooling device is closed by means of a removable insulator cover 15 whereby access may be had to the interior of the device if desired. The cooling device 10 is supported above the floor by suitable legs 16, and the bottom of the same is provided with an outlet opening 17. Arranged within the cooling device and extending the length of the same is an ammonia coil 18, the ends of which have connection with a suitable supply pipe 19 which may lead to the usual cooling pipes of the room. The outward leads of the coil are provided with valves 20 wherein the flow of ammonia to the coil may be shut off at will and the supply pipe 19 is likewise provided with a valve 21 for regulating the flow to the cooling pipes of the room or for causing the entire flow to pass through the coil 18. Entering near the top of the cooling device 10 is one end of an inlet pipe 22, the other end of which opens to the atmosphere as at 23 for permitting the fresh air to pass into the same. Mounted adjacent the ceiling of the room is an outlet or exhaust pipe 24, one end of which opens at the opposite end of the room therewith and in which the cooler is located; the other end of the pipe extending

to the outside of the building somewhere remote from the inlet 23 so that the ingoing air will not mix with the outgoing air. The outlet pipe 24 is enlarged as at 25 so as to encircle a portion of the inner pipe 22 whereby to cool the fresh air prior to its entrance into the cooling device.

In practice, fresh air is drawn from the outside of a building through the inlet pipe 22 by reason of the air in the cooling device falling to a temperature below that of the room. The fresh air enters the top of the device and passes downwardly around the ammonia coil 18 and out through the opening 17 at the bottom. In passing through the cooling device, the air in addition to being cooled is also dried, the moisture being taken up in the form of a frost which accumulates on the ammonia coil and which can be readily defrosted by shutting off the lower of the valves 20 to allow the chamber of the device to warm up. After passing through the cooling device, the air enters the room near the floor and causes the warm or stale air to rise toward the ceiling where it passes out through the pipe 24. It will be seen that so long as the ammonia passes through the coil, a continuous increase in the density and subsequent circulation of the air is set up whereby dry fresh air is being drawn into the room and the stale or moist air exhausted therefrom, thereby maintaining at all times a healthy condition of the room.

Although an ammonia coil has been shown as a cooling medium, it is to be understood that a container filled with brine may be substituted therefor and placed within the cooling device without departing from the spirit of the invention. Also, the outlet pipe 24 may extend out of the opposite side of the room and not encircle the inner pipe as shown, although, by arranging the air inlet and outlet pipes or conduits in heat-interchanging relationship, as, for example, is shown herein, the incoming fresh air is precooled and thus rendered heavier, and the outflowing foul air is correspondingly heated and thus becomes lighter, and hence the fall gained by the descent of the cooled incoming air offsets or overcomes the resistance to the upflow of the outgoing foul air, especially where the discharge point for the outflowing air, which may have a lower temperature than the outside air, is located above the level of the ceiling of the room.

The accumulating fresh incoming air, as it is dried and cooled in the enlarged chamber of the air cooling device to a temperature below that existing in the room, flows by gravity out of the bottom of this chamber and into the lower portion of the room, thus displacing a corresponding amount of the relatively lighter moist foul air from the upper portion of the room into the foul air

outlet conduit. A natural circulation of air is thus established and maintained, the amount of fresh air taken into the room being regulated automatically according to the temperature existing within the room, and there being no danger of raising the temperature within the room to a point above the desired temperature, due to the inflow of fresh air, as the fresh air cannot enter the room until its temperature has been reduced below that existing in the room.

By heat insulating the enlarged drying and cooling chamber of the cooling device from the temperature influences existing within the room, the cooling of the incoming fresh air is effected independently of the temperature of the air within the room and without any reactionary effects therefrom, as the air within the room will absorb no heat through the walls of the air cooling chamber.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A ventilating apparatus for closed rooms comprising an outflow conduit for foul air leading from the upper portion of the room directly to the outside atmosphere, a separate inflow conduit for fresh air leading from the atmosphere outside of the room to the interior thereof without communication with said outflow conduit and having an enlarged chamber therein provided with an outlet in its bottom leading to the lower portion of the room, and a refrigerating device contained in said enlarged chamber and operative to dry and cool incoming fresh air to a temperature below that existing in the room, thereby causing the cooled relatively heavier air to flow by gravity downwardly through the outlet in the bottom of said chamber and into the lower portion of the room and thereby causing a corresponding volume of foul air to discharge from the room to the outside atmosphere.

2. The combination with a closed room, of ventilating apparatus therefor comprising an outflow conduit for discharging foul air therefrom directly to the outside atmosphere, a fresh separate air inflow conduit leading directly from the outside atmosphere into the room without communication with said outflow conduit and having an enlarged chamber situated in the lower portion of the room and heat insulated from the temperature conditions existing therein, said enlarged chamber being provided at its bottom with a discharge opening, and a cooling de-

- vice contained within said enlarged chamber and operative to dry the inflowing fresh air accumulating therein and to cool such air to a temperature below that existing in the 5 room, thus causing the air so cooled to flow downwardly by gravity from such chamber and into the room and causing a corresponding volume of foul air to discharge from the room to the outside atmosphere.
- 10 3. The combination with a closed cold storage room, of ventilating means therefor comprising a foul air outlet conduit leading from the upper portion of the room directly to the outside atmosphere, a fresh air intake 15 conduit non-communicating with respect to said outlet conduit and leading into the room directly from the outside atmosphere, and means to receive fresh air from the intake conduit and to dry and cool such air independently of the influence of the temperature existing within the room, said means causing the fresh air when cooled to a temperature below that existing in the room to be discharged by gravity into the lower portion 20 of the room, thereby displacing a corresponding volume of foul air from the room and discharging it to the outside atmosphere.
- 25 4. The combination with a closed room, of ventilating means therefor comprising a foul air outlet leading from the upper portion of the room directly to the outside atmosphere, a fresh air inlet conduit separate from said outlet conduit and including an enlarged chamber situated in the lower portion of the 30 room and having an outlet in its bottom lead- ing into the room, said chamber being heat insulated from the interior of the room, and a cooling device contained within said chamber and operative to dry and cool the fresh air accumulating therein, thereby causing the fresh air, when its temperature has been reduced below that existing within the room, to flow downwardly out of said chamber by gravity through the outlet in its bottom and into the lower portion of the room.
- 35 5. The combination with a closed cold storage room, of ventilating apparatus therefor comprising a foul air outlet conduit leading from the upper portion of the room upwardly and discharging directly to the atmosphere at a point above the level of the upper portion of the room, a fresh air inlet conduit separate from said outlet conduit and leading downwardly into the room, and means for drying and cooling the incoming 40 fresh air, thereby increasing its specific gravity and thus causing such air to enter the lower portion of the room and to displace a corresponding amount of foul air from the room, the upwardly extending foul air outlet conduit and the downwardly extending fresh air inlet conduit being in heat-interchanging relationship whereby the descending fresh air will be cooled and made heavier, thereby promoting its descent, and the outflowing foul air will be heated and made 45 lighter, thereby promoting its ascent.
- 50 In testimony whereof I have affixed my signature.
- 55 ORLO G. CRANNELL.
